UNITED STATES PATENT OFFICE.

PETER PAGE, OF PAWTUCKET, RHODE ISLAND.

SAFETY-LOCK FOR WINDOWS AND THE LIKE.

1,387,302.

Specification of Letters Patent.

Patented Aug. 9, 1921.

Application filed December 23, 1918. Serial No. 268,053.

To all whom it may concern:

Be it known that I, PETER PAGE, citizen of the United States, and resident of Pawtucket, county of Providence, State of Rhode Island, have invented certain new and useful Improvements in Safety-Locks for Windows and the like, of which the following is a specification.

This invention relates to window catches or safety latches for locking together two sliding members similar to the sashes of windows and is intended to provide a device of this class which shall automatically lock the two sliding members or sashes against being forced by each other when the sashes or members are in closed position. Provision is made by which the unlocking or disengagement is readily effected to allow one sash to slide by the other while insuring the automatic locking of the sash when it is restored to locking position without further attention to the catch. By the arrangement hereinafter described the window sashes when in closed position must be automatically locked due to the mere shifting of the sash to locking position. Provision is made so that in case the catch is moved to release position when the window is open it will be impossible to close the window until the catch is restored to locking position, hence, no act of memory is required to lock the window when it is closed.

In its general feature the invention comprises a hook member secured, let us say, to the upper sash adjacent to the medial or dividing plane between the two sashes, and a latch pivotally mounted in a housing or support on the top of the lower sash in alinement with said hook, said latch being provided with two hook-engaging members one of which projects beneath the hook when in locking position and the other of which projects in line with the hook when the latch is in released or unlocked position means being provided for releasing the latch automatically to locking position when the window is closed by dropping the lower sash, and for maintaining the latch in unlocked position to permit the opening of the window by the raising of the lower sash or the dropping of the upper one.

It will be understood that the device is applicable to the locking of any two slid-

ing adjacent members although it is particularly intended for window sash use.

In the accompanying drawings I have illustrated the preferred form embodying the principles of this invention in which— 60

Figure 1 is a vertical central section showing the sashes automatically locked against opening.

Fig. 2 is a vertical side elevation showing the housings in section with the latch 65 in released or unlocked position.

Fig. 3 is a plan view showing the latch in locking position.

Fig. 4 is a horizontal section through the latch housing, a spring member showing 70 the means for holding the spring in place.

Fig. 5 is a rear elevation of the latch member.

In the practice of this invention according to the form illustrated in the drawings 75 I provide a hook member *a* provided with a forwardly projecting lip or lock-engaging member *a'* adapted to be secured to the lower cross piece of the upper sash *m* with its open side projecting inwardly from the 80 window sash but not beyond the medial or dividing plane between the two sashes extending in the direction of their sliding movement.

On the top cross bar of the lower sash is 85 mounted a housing *b* whose side walls afford support for the pivot pin or journal *e* which pivotally supports the latch *d*.

The latch *d* has a tongue or thumb piece *d'* projecting up through the top of the 90 housing *b* as shown in Figs. 1 and 3, and beyond said thumb piece is provided with an outwardly projecting portion or ledge *d''* which engages the lip *a'* when projected outwardly beyond the medial or dividing 95 plane between the sashes so as to partly overhang the upper sash. On the lower side of the pivotal center is another hook-engaging portion *d'''* so disposed as to lie on the inward side of the dividing plane 100 when the latch is in locking position but to spring forward outwardly beyond the dividing plane when the upper portion of the latch is thrown inward to sash releasing position as shown in Fig. 2. The two 105 hook-engaging members therefore form parts of an angle lever to alternately project into hook-engaging position.

Near the central pivot the latch is provided with a ledge or spring engaging por- 110

tion d^4 having angularly disposed faces the apex of which is engaged by the bow spring c to hold the latch in locked position as in Fig. 1, while the movement of the latch 5 through an angle of about sixty degrees, more or less, from locking position, serves to shift the apex or spring engaging portion of the latch to the other side of the center with relation to the spring so that 10 the latch is held in released position by the spring. In other words, when in complete releasing position, or when in complete locking position, the latch is maintained in those positions yieldingly by the 15 tension of the spring.

In the position shown in Fig. 1 the projecting hook-engaging portion or lip d^2 of the latch is beneath the lip a' of the hook member and serves to prevent the opening 20 of the window. Pressure with the finger in an inward direction against the tongue d' swings the latch into completely unlocking position as in Fig. 2 with the heel portion d^3 projecting inward in position to 25 engage the lip a' during the initial upward movement of the lower sash or downward movement of the upper sash. This heel portion d^3 is so proportioned that as it 30 comes into engagement with the lip a' it will spring the latch beyond the dead center and restore the latch to locking position at the same time allowing the window to be completely opened.

The closing of the window with the latch 35 in locking position springs the upper side of the hook member into engagement against the outer beveled surface of the latch throwing the latch back far enough to allow the sash to be returned to closed position but 40 not beyond the dead center so that immediately the lip a' has passed by, the latch springs back into locking position. The spring employed is a simple bow spring of U-shaped contour and is preferably pro- 45 vided with short side wings or extensions c' on its bottom portion to allow the spring to drop in behind the two lugs b' formed on the bottom of the housing b which serves to keep the spring correctly positioned for 50 service.

After the window is opened, if anyone should thoughtlessly open the latch to release position the heel d^3 projects beyond the lip a' so as to prevent closing of the window, and in order to close the window the latch must be restored to locking position 55 from which it yields slightly to allow the window to be closed and then snaps back into locking position automatically.

60 It will, therefore, be seen that the window can not be closed without putting the latch into locking position while it is very conveniently opened, the heel member d^3 acting automatically as a re-setting member for re- 65 storing the latch to locking position.

What I claim is:

1. The combination of two frames arranged in juxtaposition to slide by each other in parallel planes, a hook member secured to one frame close to the plane dividing the two frames, a latch pivotally mounted on the other frame and provided with two angularly disposed hook engaging portions one of which when projected beyond the dividing plane acts to lock both 70 frames against sliding movement, the other of which when projected beyond the dividing plane acts to restore the latch automatically to locking position when either sash is moved by the other, and a spring engaging 75 said latch to hold the same yieldingly on either side of its dead center of pivotal movement, substantially as described.

2. An automatic sash locking device embracing in its construction a locking hook 80 rigidly secured to one sash of the window, a latch pivotally mounted on the other sash of the window and forming essentially an angle lever either arm of which may be moved alternately into position projecting 85 beyond the medial plane of the two sash members, and a tension spring for yieldingly retaining the latch member in either position when moved in either direction beyond the dead center, substantially as described.

3. In a sash fastener the combination of a latch engaging member fixed to one sash of the window, a latch member pivotally mounted on the other sash of the window in position to engage said fixed member, 100 said latch having an interlocking projection for engaging said hook member, an angularly disposed projecting trip member arranged to restore the latch from released to locking position when the window is 105 opened, and a tension spring for holding the latch in its locking position or its extreme released position, substantially as described.

4. A sash fastener embracing in combination a hook member fixed to one sash, a pivotally mounted latch arranged on the other sash in juxtaposition to said fixed member for engagement purposes, said latch having a projection on one side of the center arranged to form locking engagement with said fixed member and having another projecting portion on the other side of the center arranged to lie in the path of said fixed member when the latch is in released position, 115 said latch being also provided with inclined faces for engaging said fixed member when the window is being closed in order to displace the latch sufficiently to allow the window to be closed and a spring arranged to 120 return the latch to locking position when the sashes are in position to be locked, substantially as described.

5. A sash fastener embracing in its construction a latch-engaging member secured 130

to one of the members to be locked, a housing secured to the other member, a latch pivotally mounted in said housing, a tension spring positioned in said housing beneath the latch to engage a portion of the latch and hold it in definite position on either side of the dead center of the spring pressure, said latch being provided with two angularly disposed projecting members adapted to alternately engage the aforesaid latch engaging member and acting respectively to lock the members against sliding apart or to restore the latch to locking position when the members are slid apart, substantially as described.

6. A sash fastener embracing in its construction a hook member fastened to one

sash, a housing fastened to the other sash adjacent to said hook member said housing being provided with retaining bosses on its bottom surface, a bow spring provided with wings projecting behind said bosses to retain the spring in position for normal action, a pivoted latch mounted in said housing and having angularly disposed projecting portions to engage said hook member, said latch being also provided with a projecting angle portion engaging said spring on either side of the direct line of pressure of said spring toward the pivotal center of the latch, substantially as described.

In witness whereof, I have subscribed the above specification.

PETER PAGE.
